UNITED STATES PATENT OFFICE.

ERNEST E. YAXLEY, OF CHICAGO, ILLINOIS, ASSIGNOR, BY MESNE ASSIGNMENTS, TO ACME CARD SYSTEM COMPANY, A CORPORATION OF SOUTH DAKOTA.

LISTING DEVICE.

1,329,568.

Specification of Letters Patent.

Patented Feb. 3, 1920.

Application filed May 28, 1914, Serial No. 841,446. Renewed September 10, 1919. Serial No. 322,988.

To all whom it may concern:

Be it known that I, ERNEST E. YAXLEY, a citizen of the United States, and a resident of the city of Chicago, in the county of Cook and State of Illinois, have invented certain new and useful Improvements in Listing Devices, of which the following is a specification.

My invention relates to listing devices for indices and the like, and more particularly to a removable transparent strip adapted to form a protective sheath or casing for a strip of paper bearing a name, telephone number or other data.

In indexing or listing systems wherein a plurality of strips bearing individual names are removably employed in connection with a casing, it is necessary to use either relatively heavy paper or card-board or to employ a transparent sheathing for the paper strip. This is particularly true of that type of indices or listing devices wherein the strips are held by inserting their opposite ends under a flange at the side of the casing, insertion being made by bending the strip so as to contract the distance between its ends to less than that of the distance between the guide flanges whereby the strip may be inserted intermediate two other strips which are already in place.

The salient objects of the invention are to provide a protective incasing strip with which a relatively thin strip of paper may be employed; to provide an incasing strip in which the paper when in position is held from accidental displacement; to permit of the easy and rapid insertion of the paper strips within the casing; to permit of a relatively narrow strip of light paper being inserted without danger of crumpling the strip; and in general to provide an improved transparent casing strip of the type mentioned.

In the accompanying drawings—

Figure 1 is a plan view of a portion of a frame showing a plurality of the casing strips in operative position.

Fig. 2 is a perspective view showing the manner of placing the paper strip within the casing.

Fig. 3 is a side elevation of the casing with the paper strip in place.

Fig. 4 is a cross-sectional view of the casing strip, and

Fig. 5 is a cross-section taken on the line $x-x$, of Fig. 1.

In Fig. 1 I have shown a suitable frame with which my casing strips may be employed. In the particular frame shown a center web 2 of sheet metal or the like is provided at its edge with inwardly extending flanges 3 and 4 and 5 and 6. The strips are formed of a length substantially equal to that between the shoulder portions 7 and 8 which are employed to offset the flanges 3 and 4 and 5 and 6 from the center web 2 a sufficient distance to receive between the web and the flanges the ends of the casing strips.

A plurality of these casing strips 9 are positioned within the frame with their opposite ends under the flanges 3 and 4 and 5 and 6, and abutting edges of each of the casing strips serve to hold them in place, as there is no chance for the casing strips to slip past one another in the frame.

Owing to the fact that the strips can be inserted by bending them to contract the distance between their ends to less than that of the distance between the flanges, the casing strips can be inserted at any point in the frame by simply pushing apart any two adjacent casing strips and inserting the new casing strip therebetween. The paper strips are also removable from the casing strip, but in transparent casings heretofore employed for this purpose, it has been necessary to insert the paper strip from the end of the casing or else to bend the paper strip parallel to its longitudinal edge which in the case of a relatively narrow strip of light material is not practical. Moreover, irregularities in the formation of the casing strip often interfere with the insertion of the light paper strip when inserted from the end.

In the present invention it is not necessary to either bend the paper parallel to its longitudinal edge nor to insert the same completely from the end. Referring in detail to the embodiment of my invention as shown in the drawings, it will be noticed that the casing strip 9 which may be formed of celluloid or other transparent material has a substantially U shaped main portion which comprises the legs 10 and 11, connected at the lower end by an integral transverse portion 12. The leg 11 of the casing strip is slightly longer than the leg 10 and

is provided at its upper end with a transverse flange 13, which preferably terminates substantially in the plane of the outer surface of the leg 10. Flange 13 is defined as 5 transverse, meaning that it is transverse to the plane of the leg 11 of the casing strip. The difference in length between the legs 10 and 11, is such that the inner surface 14 of the flange 13 is spaced from the upper 10 edge 15 of the leg 10 a distance slightly greater than the thickness of the paper which it is desired to be inserted within the casing strip.

One manner of inserting the paper strip 15 16 within my improved casing strip 9 is clearly shown in Fig. 2 and is as follows:

A corner such as 17 of the paper strip 16 is inserted in the space between the end 15 and the flange 13 and the lower edge 18 of 20 the paper strip having an angular engagement with the opening in the casing strip serves to guide the succeeding portions of the strip into place. When the entire paper strip is positioned within the casing its upper edge 19 will lie adjacent the inner surface 14 of the flange 13 and will be held thereby from lateral displacement. The strips are then placed in the frame with the leg 11 of the U shaped casing at the front 25 thus giving an unobstructed transparent surface through which the reading material on the strip may be observed.

While it is obvious from Fig. 2 that the paper strips can also be inserted and removed from the end if desired, my improved casing permits of the use of lighter paper and the more rapid insertion of the strips than is possible with devices in which the paper must be inserted from the end. 30 Although I have shown a particular embodiment of my invention, I do not desire to be limited to the particular construction shown except as specified in the claims.

I claim:
45 1. The combination with a flexible design-

nation strip, of a relatively long and narrow transparent protective casing for removably receiving said strip, said casing having a substantially U-shaped cross section and one leg of the U being longer than 50 the other and a flange on the longer leg extending in angular relation thereto and over the other leg of the U and terminating substantially in the plane thereof, said flange being spaced from the upper edge of the shorter leg of the U a sufficient distance to leave a lateral opening adapted to receive the designation strip within the casing when said strip is substantially the same width as the inner width of the casing. 55

2. The combination with a flexible designation strip, of a flexible transparent protective casing for removably receiving said strip, comprising a relatively long and narrow member of substantially U shaped cross 60 section having an inside width substantially the width of the flexible strip, having at one edge an integral flange extending at substantially right angles to the sides of the protective casing and spaced from the upper edge of one of the sides to provide an opening through which the strip can be guided into position within the casing. 65

3. The combination with a designation strip, of a flexible transparent protective 70 casing for removably receiving said strip, comprising a relative long and narrow member having substantially parallel slightly spaced apart sides, a transverse connecting portion, integrally connecting two of the 75 adjacent edges of said side members, one of such side members being relatively straight throughout its length and the other of said side members having an integral flange extending at substantially right angles to the 80 sides of the casing. 85

ERNEST E. YAXLEY.
